UNITED STATES PATENT OFFICE.

JOHN SWANSON, OF MOBILE, ALABAMA.

BOILER-FURNACE.

1,209,070.

Specification of Letters Patent. Patented Dec. 19, 1916.

Application filed January 17, 1916. Serial No. 72,566.

To all whom it may concern:

Be it known that I, JOHN SWANSON, a citizen of the United States, residing at Mobile, in the county of Mobile and State of 5 Alabama, have invented new and useful Improvements in Boiler-Furnaces, of which the following is a specification.

The present invention relates to improvements in boiler furnaces.

10 In carrying out my invention it is my purpose to construct a furnace for boilers wherein the heat units will be distributed to the top and sides of a furnace wall so that the water at the bottom of the boiler will be 15 heated simultaneously with the water at the top and sides of the furnace and whereby a proper circulation of the water under the bottom of the furnace will be created.

It is also my purpose to construct a tubular furnace for boilers including angular side grates and a connecting dome grate each adapted to receive a bed of fire, the arrangement being such as to materially increase the heating capacity as compared with 25 the ordinary construction of such devices.

A further object of the invention is to construct a tubular furnace and to arrange the same longitudinally of a boiler, to provide the furnace with a plurality of angularly arranged side grate members and an arched grate member connecting the upper side grates, each of the grates receiving a fire bed and the upper arched shaped grate comprising movable members which may be arranged to bring the fire in close contact with the top of the furnace to create a greater or determined amount of heat at this portion of the furnace.

With the above and other objects in view, 40 the improvement resides in the construction, combination and arrangement of parts set forth in the following specification and falling within the scope of the appended claims.

In the drawings, Figure 1 is a view of a 45 boiler provided with my improved furnace, Fig. 2 is an enlarged horizontal sectional view approximately on the line 2—2 of Fig. 1, Fig. 3 is a vertical longitudinal sectional view on an enlarged scale, and taken approximately on the line 3—3 of Fig. 1. Fig. 4 is a transverse sectional view approximately on the line 4—4 of Fig. 3, Fig. 5 is a perspective view of a portion of the tubular furnace and the grate therein, and Fig. 6 is 55 a view illustrating the upper grate members

raised to bring the fire close to the top of the furnace.

Referring now to the drawings in detail, the numeral 1 designates a tubular steam boiler, and arranged adjacent the bottom of the boiler and extending longitudinally therewith is a pair of spaced tubes 2—2. Each of these tubes 2 provides a casing for the furnace, and the outer ends of each of the tubes is closed by a plate 3 having an enlarged opening adjacent the upper end thereof closed by a door 4 and a smaller side opening closed by doors 5—5 as well as a central opening closed by a door 6.

Arranged in each of the casings 2 is a grate of peculiar formation constructed in accordance with my invention. The grate is constructed to provide a plurality of fire boxes, and in reality a plurality of grates. The grate sections comprise side members 75 and an upper arched connecting member. The sides, in the showing of the drawings, include two grates each comprising a horizontal shelf and an obtuse angular extension terminating in a flat plate or side member 80 which projects above and is connected with the superimposed shelf of the upper grate, and the side members of the said upper shelf are likewise connected to or form a support 85 for the longitudinal edges of the said upper grate.

The lower shelf members, indicated by the numerals 7, rest upon transverse cleats 8 disposed upon the inner end of the furnace casing, and which may be likewise disposed 90 at other points best suited for supporting the said shelves 7. The grate members are of the herring-bone class and the inner ends of each of the shelves 7 is formed with an inwardly extending upwardly inclined grate 95 extension 9 that terminates in a co-extensive flat non-pervious side 10. The side 10, at its opposite ends, is provided with angularly arranged ears 11 that are bolted to the end plates of the furnace, and the sides 10 project a suitable distance above the horizontal shelves 12 of the upper side grate members.

The ends of these grate members are supported upon the transverse cleats 13 arranged at the ends of the tubular furnace 105 and one of the longitudinal edges of each of the shelves 12 contacts with the side plates 10 of the respective grates 7. The grates of the shelves 12 are also of the herring-bone construction, as are their inwardly 110

extending angularly arranged portions 14. The angular portions 14 terminate in co-extensive non-pervious flat plates 15 which have their ends provided with ears 16 which 5 are bolted to the end plates of a furnace, and the sides 15 extend a suitable distance above the longitudinal ends of the dome-shaped upper grate 17. The grate 17 has its longitudinal edges contacting with the side plates 10 15 and its ends are supported upon curved cleats 18 which are secured to the opposite ends of the furnace. The upper dome-shaped grate 17 is also of the herring-bone construction and preferably comprises two grates 19 15 and 20 respectively, and these grates may be raised toward the top of the furnace to bring the bed of fire closer to the said top so that a greater amount of heat may be thus applied to the top. The ash pit, indicated 20 by the numeral 21, is disposed below the grates. To operate the grates 19 and 20, a rod *a* may be journaled in suitable bearings and have eccentrically arranged thereon wheel or roller members *b*. The end of the 25 rod *a* may extend through a suitable opening in the outer face of the boiler and is shaped to receive the angular socket of an ordinary shaker handle. When the rod is revolved in one direction the cam or eccentric members *b* will contact with the grates 30 19 and 20, and when the rod is revolved in the other direction, the grates will drop by gravity upon their supporting cleats 18.

The ashes and clinkers from the grate 35 members 19 and 20 which do not fall directly into the ash pit 21 will contact with the inclined sides 15 of the upper grate members 12 and be directed thereby to the center of the ash pit. The ashes which fall from the 40 grate 12 will contact with the angular sides 10 of the grate 7 and will likewise be centrally delivered to the ash pit 21. The doors 5 provide admission to the fire boxes for the 45 grates 7 and 12, the door 4 for the central grate 17, while the door 6 closes the entrance to the ash pit.

From the above description, taken in connection with the accompanying drawings, the simplicity of the device, as well as the

advantages thereof will, it is thought, be 50 perfectly apparent to those skilled in the art to which such invention appertains without further detailed description.

Having thus described the invention, what I claim is:

1. In a furnace for boilers, a tubular casing, spaced side grates in the casing, said side grates including each a horizontally straight grate portion, an angular grate portion connected with the inner end thereof and overlying the said shelf, a non-pervious side plate co-extensive with the angular grate portions and extending above the horizontal shelf portion of the adjacent grate, and an upper grate member connected with the upper side plates. 55

2. A grate for boilers including a tubular casing, side grates in the casing, each of said side grates including horizontal grate bars and angular grate bars formed in the inner 60 ends of said horizontal grate bars and extending angularly over the same, non-pervious side plates co-extensive with the angular 65 grate bars and projecting above the horizontal members of the adjacent grate sections, and a dome-shaped grate connecting the side plates of the upper grates below the upper edges of the same. 70

3. A grate for boilers including a tubular casing, side grates in the casing, each of 75 said side grates including horizontal grate bars and angular grate bars formed at the inner ends of said horizontal grate bars and extending angularly over the same, non-pervious side plates co-extensive with the 80 angular grate bars and projecting above the horizontal members of the adjacent grate sections, and a dome-shaped grate connected with the side plates of the upper grates below the upper edges of the same, said dome-shaped grate comprising a plurality of 85 independent members. 90

In testimony whereof I affix my signature in presence of two witnesses.

JOHN SWANSON.
